United States Patent Office.

HAMILTON PRAY, OF SHARON, CONNECTICUT.

Letters Patent No. 97,441, dated November 30, 1869.

IMPROVEMENT IN OPERATING GRINDSTONES.

The Schedule referred to in these Letters Patent and making part of the same.

To all whom it may concern:

Be it known that I, HAMILTON PRAY, of Sharon, in the county of Litchfield, and State of Connecticut, have invented a new and useful Improvement in Operating Grindstones; and I do hereby declare that the following is a full, clear, and exact description thereof, which will enable others skilled in the art to make and use the same, reference being had to the accompanying drawings, forming part of this specification.

This invention relates to a new and improved mode of operating revolving grindstones, whereby one person is enabled to turn or revolve the stone, and to hold the article to be ground; and

It consists in operating or revolving the stone by means of pedals (or treadles) attached to cranks on the grindstone-shaft, arranged in the manner hereinafter described.

In the accompanying drawing—

Figure 1 represents a side view of the arrangement.

Figure 2 is a vertical section through the line x x of fig. 1.

Figure 3, a double crank-shaft for the grindstone.

Similar letters of reference indicate corresponding parts.

A is the grindstone.

B is the frame or bench, on which the stone is supported.

This bench rests on timbers C C, which extend forward, so that one end of the pedals may be supported therefrom.

D D represent the pedals.

These pedals are hinged to the forward part of the frame-timbers C C, as seen at E, but should the grindstone be placed in a permanent position, the

pedals may be attached to the floor, or to any other convenient fixture.

Each end of the grindstone-shaft is provided with a crank, as seen in fig. 3, or with crank-wheels G G, as seen in the other figures.

F F represent connecting-rods from the back ends of the pedals to the cranks, as seen in the drawing.

The pedals are guided, so that they have no lateral movement, by means of the fixed vertical rods H H, which pass through mortises in the pedals.

In revolving the stone, the operator stands upon these pedals (one foot on each) and bears with his weight alternately on the pedals, thereby revolving the stone by means of the cranks and connecting-rods F F.

I represents a rest, which is attached to the bench B, to steady the tool when being ground.

J is the grindstone-shaft.

By this arrangement, a person is enabled to turn the stone with his feet, (and weight,) while his hands are left at liberty to hold the tool, or other article, which he wishes to grind.

The advantages of this arrangement are many, and must be obvious to all.

Having thus described my invention,

I claim as new, and desire to secure by Letters Patent—

A grinding-apparatus, composed of grindstone A, bench-timbers B C, hinged pedals D, crank-disks G, connecting-rod F, rest I, and shaft J, all constructed and arranged with respect to one another, in the manner described.
